UNITED STATES PATENT OFFICE.

GEORGE F. PAGE, OF CONCORD, NEW HAMPSHIRE.

MACHINE FOR STRETCHING BELTING.

SPECIFICATION forming part of Letters Patent No. 373,847, dated November 29, 1887.

Application filed June 8, 1887. Serial No. 240,669. (No model.)

To all whom it may concern:

Be it known that I, GEORGE F. PAGE, a citizen of the United States, residing at Concord, in the county of Merrimac and State of New Hampshire, have invented certain Improvements in Machines for Stretching Leather Belting, of which the following is a full, clear, and exact description, reference being had to the accompanying drawings, making part of this specification, in which—

Figures 1 and 1^a are plans of a machine for stretching leather belting, constructed in accordance with my invention. Figs. 2 and 2^a are side elevations of the same. Fig. 3 is a 15 transverse vertical section on the line x x of Fig. 1. Fig. 4 is a side elevation of the belt-tightener used in connection with the take-up roll. Fig. 5 is a side elevation (enlarged) of the tension device by which the belting is kept 20 in contact with the resistance-rolls. Fig. 6 is a detail.

My invention relates to machines for stretching leather belting; and it consists in certain novel combinations of parts and details of construction, as hereinafter set forth and specifically claimed.

In the said drawings, A represents the frame of the machine, in suitable bearings in which run the shafts of the different rolls, to be hereinafter described, which act upon the belting in its passage through the machine. The finished belting a to be stretched is taken from the coil B, in which form belting is usually rolled up after it is made for convenience in handling, the coil B being supported between standards b b, placed close to the front end of the machine. If preferred, however, the belting may lie loosely on the floor instead of being disposed in the form of a coil. The belting a as it enters the machine passes between two rods or bars, c c, and also between suitable gages, d d, placed upon the upper bar c and made laterally adjustable thereon, which gages keep the belting in its proper position 45 in line with the coil B. Thence the belting passes through a suitable friction or tension device, which may consist of a pair of rolls held either rigidly or by springs.

In practice I employ a pair of rubber rolls, 50 i i, which are adjusted to exert more or less pressure by means of screws e e, and these

rolls, in order to accommodate themselves to different thicknesses in the length of the belting, also act under adjustable springs 10. After passing through the tension device just described, the belting a is brought into contact with one or more resistance rolls or pulleys, f. In practice I prefer to use two, as shown in the drawings. A guide-roll, g, is preferably interposed between the tension device and the 60 first resistance-roll, in order to secure as great a surface-contact as possible of the belting with the said resistance-rolls. The belting passes partially around each of these resistance-rolls f f, which may be adjusted in any desired positions relative to each other, and the tension-rolls i i may be adjusted to hold the belting in contact with the resistance-rolls with more or less force, as desired. A single resistance-roll or more than two may be employed; but I find 65 two such rolls adjusted in the positions shown to answer a good purpose. These resistance-rolls act precisely in the same manner as the driven pulley of a machine, or a counter-shaft to which the load is attached.

In order to vary the load or work upon the resistance-rolls, and thereby graduate or control the strain for belting of different thicknesses or widths, I apply any suitable brake mechanism thereto. In practice I provide the 80 shaft of each resistance-roll f, outside the frame-work, with a smooth-faced pulley, h, over which is drawn a friction-strap, C, attached to a treadle, D, by depressing which the strap is caused to act as a brake, whereby 85 the load or resistance can be increased or diminished according to the character of the belting being stretched and the amount of strain which it is desired to put upon it. The belting, after leaving the last resistance-roll f, 90 passes alternately under and over a series of rolls, m, which assist in stretching the belting in a well-known manner, and are of such diameter and so arranged as not to bend the belting at too abrupt an angle, but only in a 95 natural curve, thus avoiding the "breaking up" or injuring of the belting by bending it too sharply. These rolls of themselves, however, form no part of my invention, and may be omitted, if desired, although I prefer to use 100 them, as they effect a more thorough and permanent stretching of the belting. Each of the

rolls *m* is provided at one end with a flange, *n*, which serves to guide one edge of the belting, the opposite edge of which is kept in place by a long guide-bar, *G*, supported by horizontal transverse rods 12, sliding in suitable bearings in the frame-work *A* and made adjustable toward and from the side of the same, the rods 12 being held in place when adjusted by screws *p*. This adjustable guide-bar *G* is of greater width than the diameter of the rolls *m*, and is provided with suitable apertures to allow it to slide freely over the said rolls, whereby each roll is provided with a movable or adjustable flange or guide opposite to its stationary flange *n*. From the rolls *m* the belting is carried partially around one or more large traction or drawing rolls or pulleys, *H*, which act upon the belting in the same manner as an ordinary driving-pulley in machinery and cause the belting to turn the resistance roll or rolls *f* as it passes around them; and it will be obvious that as the rotation of the resistance-rolls is retarded more or less by the action of their brake mechanism, the belting will be stretched more or less as it is drawn forward by the traction rolls or pulleys *H*. For convenience I employ three drawing or traction rolls or pulleys, as shown; but a single large one or a series of any suitable number may be used, arranged in any desired manner with respect to each other. I prefer to arrange these pulleys as shown, as by this means I secure a large friction or traction surface without unnecessarily increasing the length of the machine.

In the drawings the shafts of the traction-rolls are provided, outside the frame-work, with gears *I*, which mesh with each other, the central gear *I* being driven by a pinion, *q*, (shown dotted in Fig. 2^a.) on the driving-shaft *r*, which carries the fast and loose pulleys *s t*, and in this manner the traction-pulleys are caused to revolve continuously at a uniform rate of speed while the machine is in operation, thus producing a uniform motion of the belting in the operation of stretching and testing; and as these pulleys are set in motion the belting is drawn through the machine, and causes the resistance-rolls to revolve under the control of the friction-brake, a tension being thus put upon the belting, the same as if it were in actual use; and this tension may be made, if desired, to exceed that to which the belting would ever be subjected when employed in driving machinery. After the belting leaves the traction or drawing rolls it is wound upon a take-up roll, *u*, which also accomplishes another purpose—viz., that of keeping the belting in contact with the traction pulley or pulleys, the same as a belt is kept in contact with a driving-pulley in use. The roll *u* is revolved to take or wind up the belting just as fast as it is delivered by the traction-rolls by means of a pulley, *v*, on its shaft *w*, which is driven by a crossed belt, *a'*, passing over a pulley, *b'*, on the driving-shaft *r* or other suitable rotating shaft of the machine,

so that when the traction-pulleys are in motion the winding-shaft *w* will also be driven; but since the belting moves forward at a uniform rate of speed it will be evident that as the coil upon the take-up roll *u* is constantly increasing in diameter the speed of the winding-shaft must be constantly diminished; and to accomplish this the belt *a'* is allowed to slip with sufficient freedom to permit the belting to be wound upon the take-up roll with any desired amount of tension, this being accomplished by means of an idler or belt-tightener, *L*, which may be of any suitable construction to accomplish the desired end, the tension being varied at the will of the operator.

The belt-tightener *L* shown in the drawings and which I prefer to use consists of an arm or lever, 24, pivoted at 25 to the frame-work, 85 and carrying a small wheel, 26, which rests upon the belt *a'* with a pressure due to the weight of the lever 24, which is sufficient to produce the required degree of friction between the belt *a'* and the pulleys *v b'* to cause 90 the motion of the pulley *b'* to be communicated to the pulley *v*. When an additional tension on the belt *a'* is desired, the lever 24 is depressed by the hand more or less and secured by a pin, 27, placed in one of the holes 28 in the frame-work, and by raising the lever 24 sufficiently to entirely remove the wheel 26 from contact with the belt *a'* the latter will be left so loose that the pulley *v* will remain at rest.

In practice I find it desirable to have only 100 sufficient tension put upon the belting being stretched to wind it into a coil upon the take-up roll *u* without producing any appreciable amount of strain thereon and to keep it in contact with the traction-rolls with sufficient 105 force to create the necessary friction to enable said traction-rolls to draw the belting forward through the machine.

The take-up roll *u* is provided with a longitudinal groove, 15, or other device for holding 110 the end of the belt and preventing it from slipping during the winding up of the first coil on the said take-up roll.

M is a frame, one end of which is pivoted at 115 *d'* to uprights *e'*, rising from the frame-work, the free end of the frame *M* carrying a guide-roll or "rider," *N*, provided with stationary and adjustable flanges *g' h'* for guiding the belting at its edges and preventing it from running off to one side, thereby keeping the coil on the 120 take-up roll *u* even, the guide-roll *N* resting on the belting at all times and rising with the pivoted frame as the coil of belting increases in diameter.

I do not confine myself to the method shown 125 of operating the take up roll by means of a belt, *a'*, from the driving-shaft, as it may be operated by friction-pulleys adapted to slip as the size of the coil of belting increases, or by an independent machine or other mechanism 130 so connected with the take-up roll as to keep the belting in contact with the traction-rolls and wind it up as fast as it is delivered from the latter. When belting is drawn through a

stretching-machine against resistance applied thereto, and this drawing is effected by winding the belting in a coil upon a shaft or roll with a direct and unyielding pull, the inner 5 coils will be drawn much tighter than the outer ones, which objection is entirely obviated in my improved machine, in which the forward motion of the belting is effected by traction-rolls and the belting coiled or rolled 10 up with only sufficient tension to cause it to be taken up as fast as it is delivered by said traction-rolls.

By means of my improved machine the belting is thoroughly tested as to workmanship, 15 quality of leather, &c., in the same manner as if in actual use—a desideratum hitherto unattained—all the "stretch" usually taken out of a belt in the early period of its use being removed, whereby it is materially improved on 20 account of its being subjected to a running test, and much trouble and annoyance are thereby saved to the purchaser when the belting is put into actual use.

After placing the coil or roll of belting in position at the rear end or starting point of the machine, the tension or friction rolls are separated by turning out the adjusting screws, which allow their springs to act. The belting to be stretched is then passed by hand between 30 the tension-rolls and put in position throughout the whole length of the machine, being drawn through by hand, and as it is drawn through it is put over one roll and under the next until it reaches the traction-rolls. 35 Here it is passed in the same manner under and over the rolls in position, as shown, until it is connected with the take-up or winding roll, one end of the belt being simply set into the longitudinal groove of the take-up 40 roll. It is not fastened; but simply slipped into the groove, then as it is wound it does not slip out. After this has been done the upper friction or tension roll at the rear end of the machine is screwed down onto the belting. 45 The first end of the belt is not stretched as it is passed this time through the machine, for it is necessary to get it through by hand in position to start the entire machine at once. The friction-rolls, it will be understood, are 50 not feed-rolls, and do not perform any office except as friction or tension rolls to hold the belt in contact with the resistance-rolls. The belt is ready to start after the first end is drawn through the machine and connected with the 55 winding-roll, as above described. This roll of belting, after being run through once, (in which it is all stretched except so much of the first end as is necessary to pass through the machine to make the connection with the 60 take-up or winding roll before the machine is started,) is then put through the machine again, the other end to, or commencing the second time at the opposite end of the belting.

What I claim as my invention, and desire to 65 secure by Letters Patent, is—

1. The combination of one or more traction

or drawing rolls and mechanism for driving the same for producing a forward movement of the belting to be stretched through the machine by frictional contact with its surface, a 70 device comprising a take-up roll for keeping the belting in contact with the traction roll or rolls, a resistance device consisting of one or more rolls or wheels against the surface of which the belting is held, a brake mechanism comprising a belt applied to the resistance roll or rolls for retarding the movement of the same, and tension-rolls adapted to hold the belting in contact with the resistance roll or rolls, all 75 operating substantially in the manner and for 80 the purpose set forth.

2. The combination of one or more traction or drawing rolls and mechanism for driving the same for carrying the belting to be stretched through the machine by frictional contact with 85 its surface, a take-up roll adapted to receive and wind up the belting as fast as it is delivered by the traction device and keep it closely in contact with the latter, a resistance device consisting of one or more rolls or wheels against 90 the surface of which the belting is held, a brake mechanism comprising a belt and operating-treadle for retarding the movement of the resistance roll or rolls, and tension-rolls for holding the belting in contact with the resistance 95 device, substantially as described.

3. The combination of one or more traction or drawing rolls and mechanism for driving the same for carrying the belting to be stretched through the machine by frictional contact with 100 its surface, a device comprising a take-up roll for keeping the belting in contact with the traction roll or rolls, a resistance device consisting of one or more rolls or wheels against 105 the surface of which the belting is held, a brake applied to the resistance-rolls for retarding the movement of the same, a series of rolls, *m*, arranged between the traction or drawing rolls and the resistance-rolls, and a tension device comprising the rolls *i i*, for holding the 110 belting in contact with the resistance-rolls, all operating substantially in the manner and for the purpose set forth.

4. The combination, with the traction or drawing device, the device for keeping the 115 belting in contact therewith, the rolls *m*, the resistance device, and its brake mechanism, of a tension device made adjustable to hold the belting in contact with the resistance device with more or less force, substantially as 120 described.

5. The combination, with the traction or drawing roll or rolls and a resistance device controlled by a brake mechanism, of a take-up roll, a belt-tightener, and the pulley or pulleys whereby the take-up roll is caused to produce a slight tension on the belting at all times to insure its being wound up as fast as delivered by the traction device, substantially as 125 described.

6. The combination, with the traction or drawing roll or rolls and a resistance device 130

controlled by a brake mechanism, of the take-up roll u , with its shaft w and pulley v , the belt a' , passing over said pulley v and the pulley b' and adapted to slip on the said pulley 5 or pulleys as the coil of belting on the take-up roll increases in diameter, and a tightening device applied to the belt a' , whereby the tension produced by the take-up roll u on the

belting being wound up thereon may be varied, substantially as described.

Witness my hand this 2d day of June, A. D. 1887.

GEORGE F. PAGE.

In presence of—
P. E. TESCHEMACHER,
EDWIN F. EDGETT.
